US00D542500S

(12) **United States Design Patent** (10) **Patent No.:** **US D542,500 S**
Perrier et al. (45) **Date of Patent:** **** May 8, 2007**

(54) **DISPLAY DEVICE**

(75) Inventors: **R. Sylvain Perrier**, Ottawa (CA); **Jeremy List**, Ottawa (CA); **Cliff Read**, Carp (CA); **Jason Busschaert**, Towson, MD (US); **Mark Edey**, Ottawa (CA); **James D. Miller**, Holland Landing (CA); **Howard W. Overland**, Aurora (CA)

(73) Assignee: **Springboard Retail Networks Inc.**, Ontario (CA)

(**) Term: **14 Years**

(21) Appl. No.: **29/241,458**

(22) Filed: **Oct. 28, 2005**

(30) **Foreign Application Priority Data**

Apr. 29, 2005 (CA) 110971

(51) **LOC (8) Cl.** **12-02**

(52) **U.S. Cl.** **D34/27**

(58) **Field of Classification Search** D34/12-27;
40/308, 506; 280/33.992, 33.991; D14/341,
D14/374, 100; D20/10, 43; 235/383; D19/26;
D16/225

(57) **CLAIM**

The ornamental design for a display device, as shown and described.

DESCRIPTION

FIG. 1 is a front right perspective view of the display device; FIG. 2 is a rear perspective view of the display device of FIG. 1;

FIG. 3 is a top plan view of the display device of FIG. 1; FIG. 4 is a bottom plan view of the display device of FIG. 1;

FIG. 5 is a front elevation view of the display device of FIG. 1;

FIG. 6 is a rear elevation view of the display device of FIG. 1;

FIG. 7 is a left side view of the display device of FIG. 1; and, FIG. 8 is a right side view thereof.
